[57] CLAIM

The ornamental design for a revolver sight, as shown and described.

DESCRIPTION

FIG. 1 is right side and rear perspective view of a revolver sight showing my new design in its environment;
FIG. 2 is a top plan view of a revolver sight showing my new design;

FIG. 3 is a front elevational view thereof;
FIG. 4 is a rear elevational view thereof;

FIG. 5 is a left side elevational view thereof, the right side being a mirror image of the side shown; and,

FIG. 6 is a bottom plan view thereof.

The broken line showing of a portion of a revolver in FIG. 1 is for illustrative purposes only and forms no part of the claimed design.
